UNITED STATES PATENT OFFICE.

SAMPSON W. MOON, OF CHICAGO, ILLINOIS.

ELECTRIC SAFETY RAZOR.

Application filed August 8, 1925. Serial No. 48,930.

My invention relates to electric safety razors and contemplates improved features of construction and arrangement which will produce a light, compact and conveniently manipulated device and a device which may be connected directly with the ordinary electric light circuit, and which is devoid of all contacts and which is efficiently sealed against the entrance of moisture and dust.

10 A structure embodying the various features of the invention is disclosed on the drawings, in which:

Figure 1 is a side elevational view of the device;

15 Fig. 2 is a side view of the device with the enclosure shell in cross section;

Fig. 3 is an end view;

Fig. 4 is a side elevational view taken on a plane at 90 degrees with the plane of the 20 side view, Figure 2, and

Fig. 5 is a sectional view on the plane 5-5, Figure 5.

The device is of that class in which the shaving or other tool is carried by an armature which is caused to rapidly vibrate in synchronism with the current alternation in an alternating current electromagnet structure. The enclosing and grip frame for the device comprises the conical head 10 and the cylindrical sleeve 11 having threaded engagement at its front end with the threaded base 12 of the head. The head and shell are of insulating material such as bakelite. Secured to the inner side of the

35 head 10 by screws 13 is the annular plate 14 of magnetic material forming the yoke of the electromagnet cores 15 and 16 which are secured to the plate by screws 17, as clearly shown in Fig. 4. These cores support the

40 energizing coils 18 and 19, the cores extending rearwardly from the head in substantially parallel relationship and being deflected laterally at their outer ends to form the poles 20 and 21. Between these poles

45 extends the outer end of the armature tongue 22 whose inner end is secured in a sleeve 23, this sleeve being secured at its inner end to the outer end of the L-shape spring 24 whose inner end is secured to the

50 plate 14 by means of screws 25, or otherwise, the spring and sleeve 23 being preferably of non-magnetic material. The spring supports the armature tongue for swinging or vibratory movement to respond to the mag-

55 netic changes in the electromagnet cores,

and as alternating current is used for operating my device, the armature tongue is preferably polarized and its weight and the spring adjusted so that the armature can vibrate in synchronism with the frequency 60 of the alternating current flowing through the coil. To prevent sticking of the armature against the poles and also to deaden any impact noises, the end of the armature tongue is enclosed by a sleeve 26 of non-magnetic material such as rubber.

Secured to the pole ends of the electromagnet cores is the annular plate 27 of non-magnetic material, and the plate may be secured to these cores as by soldering. Secured to the plates by means of screws 28 is the cylindrical block 29 from which extend the terminal pins 30 and 31 connected with the electromagnet winding by means of leads 32 and 33. The block 29 forms a support for the outer end of the enclosure sleeve 11 having in its face the opening 34 into which the terminal pins extend and into which a suitable terminal plug may be inserted to receive the pins and convey electric 80 current thereto. To protect the apparatus from moisture or dust, a washer 35 of rubber or other suitable material is inserted between the base of the sleeve and block 29, as clearly shown in Figs. 3 and 4. The outer 85 ends of the terminal pins are also a distance within the ends of the sleeve so that they will be protected from injury.

The head 10 has the axial passageway 36 through which extends the tool supporting post or bar 37 which, at its inner end, is deflected laterally and bifurcated to receive the spring 24 and to be readily secured to the spring as by means of soldering. With this arrangement, vibration of the armature tongue will be communicated to the supporting post and to the tool supported thereon. The tool, shown, is a razor, the supporting frame 38 having the plate 39 between which and the plate 40 is secured the razor blade 41. The frame 38 has the threaded stem 42 secured by the threaded coupling 43 to the outer end of the post 37 so that the frame will partake of the armature vibration. The frame is shown secured to the armature structure so that it will vibrate longitudinally relative to the blade, although connection could be made so that the blade would vibrate transversely or diagonally. To prevent moisture from entering into the 100 105 110

enclosing housing, a sleeve 44 of rubber may be applied around the coupling 43 and the end of the head 10, the head having the head 45 which serves to securely hold the sealing sleeve in place. The sleeve may be of sufficiently thin material so as not to interfere with the vibration movement of the armature structure.

The device of my invention is light and 10 compact and conveniently manipulated. There are no contacts within the device as the electromagnet coils are directly and permanently connected with the alternating current energizing circuit when a circuit 15 socket is applied to the terminal pins 30 and 31. The arrangement and adjustment is such that the armature will respond accurately and smoothly to the electromagnetic impulses caused by the alternating current flow through the coils and the tool is 20 therefore given a smooth vibratory movement. Instead of a shaving tool, massaging or other tools may be applied to the end of the post 37. By means of the washer 35 25 and the rubber sleeve 44, the structure is secure against entrance of moisture or dust to the inside of the housing. Changes and modifications can be made without departing from the scope of my invention and I 30 do not, therefore, limit myself to precisely what I have shown and described.

I claim as follows:

1. In a device of the class described, the 35 combination of a head, a yoke plate secured thereto, electromagnet cores extending from said plate and secured thereto, the outer ends of said cores being shaped to form poles, an armature tongue having its outer end disposed between said poles, a spring secured 40 to said yoke plate and said armature tongue being secured to said spring whereby said tongue will be supported to vibrate, and a tool supporting stem extending from said spring and through said head.

2. In a device of the class described, the 45 combination of an enclosure comprising a head and a shell having detachable engagement therewith, a yoke plate secured to the inner side of said head, electromagnet cores 50 extending from said plate and secured thereto, coils on said cores, the outer ends of said cores being deflected laterally to form opposed poles, an armature tongue having its outer end interposed between said poles, a spring secured to the inner end of said armature tongue and supported on said yoke plate whereby said armature may vibrate in 55 response to electromagnetic variations in said cores, said head having a passageway, 60 a tool supporting stem extending through said passageway and adapted at its outer end to receive a tool, the inner end of said stem being secured to said spring whereby 65 said stem will partake of the vibrations of said armature, and a terminal block secured

to the outer ends of said cores and terminal pins on said block connected with the electromagnet coil windings

3. In a device of the class described, the 70 combination of an enclosing housing comprising a conical head and a cylindrical sleeve having detachable connection therewith, an electromagnet structure extending from said head through said sleeve and terminating at its outer end in a pole, an armature tongue opposed at its outer end to said pole, said armature tongue being polarized, a spring structure supporting said armature tongue at its inner end from said head whereby said armature tongue may vibrate 75 in response to magnetic variations in said electromagnet, and a tool supporting stem extending from said spring through and to the exterior of said head for partaking of the vibratory swing of said armature tongue. 80

4. In a device of the class described, the 85 combination of an enclosure comprising a conical head and a detachable cylindrical sleeve, said head and sleeve being of insulating material, a yoke plate secured to the inner side of said head, an electromagnet structure extending from said yoke plate through said sleeve and terminating in poles, an armature tongue interposed at its outer end between said poles, a spring structure extending from said yoke plate and secured to said armatures whereby said armature will be suspended to vibrate in response to magnetic changes in said electromagnet structure, said head having a passageway 90 therethrough, a tool supporting stem extending through said passageway and secured at its inner end to said spring to partake of the vibration of said armature, said sleeve having an opening in its base, and terminal pins extending said electromagnet structure through said opening for detachable connection with an electrical circuit. 95

5. In a device of the class described, the 100 combination of an enclosing housing comprising a head and a cylindrical sleeve detachably applied thereto, an electromagnet structure extending through said sleeve and supported on said head, an armature opposed between the pole ends of said electromagnet 105 structure, means supporting said armature for vibration in response to magnetic changes in said electromagnet structure, said head having a passageway, a tool supporting stem extending through said passageway and having connection with said armature to partake of the vibrations thereof, a terminal block supported by the outer end of said electromagnet structure, terminal pins on 110 said block connected with the electromagnet winding, said sleeve having an opening in its base and said terminal pins extending through said opening for connection with an external circuit, a sealing washer between 115 said terminal block and said sleeve, and a 120

125

sealing sleeve between said tool supporting post and said head.

6. In a device of the class described, the combination of an electromagnet core structure having poles, an armature supported on said structure to vibrate and having its outer ends interposed between said poles, an enclosure head secured to one end of said electromagnet structure and having a passageway therethrough, a tool supporting stem extending through said passageway and connected at its inner end with said armature to partake of the vibratory movement thereof, a terminal block secured to the other end of said electromagnet structure, terminal pins on said block connecting with the winding of the electromagnet structure, and an enclosing sleeve supported at its outer end on said block and having detachable connection 20 at its inner end with said head.

extending therefrom, windings on said cores, the outer ends of said cores being deflected 25 laterally and parallel with each other to form opposed pole pieces, an armature tongue parallel with said cores and in a plane intermediate thereof and having its outer end disposed between said pole pieces, 30 a vibratory spring secured to said yoke and to the inner end of said armature, said armature being polarized whereby it will vibrate in response to alternating current flow 35 through said windings, an enclosure head secured to said yoke, said head having a passageway, a tool supporting stem extending through said passageway and connected with said armature to partake of the vibratory movement thereof, and an enclosing sleeve 40 having detachable connection with said head, said sleeve enclosing said electromagnet and armature structures.

In witness whereof, I hereunto subscribe my name this 4th day of August, 1925.

SAMPSON W. MOON.
